UNITED STATES PATENT OFFICE.

MATHIAS SMOLIK, OF PITTSBURGH, PENNSYLVANIA, ASSIGNOR, BY DIRECT AND MESNE ASSIGNMENTS, TO ECONOMY SPECIALTIES COMPANY, A CORPORATION OF DELAWARE.

LINE-HOLDER.

1,223,908.

Specification of Letters Patent. Patented Apr. 24, 1917.

Application filed August 19, 1916. Serial No. 115,793.

To all whom it may concern:

Be it known that I, MATHIAS SMOLIK, a citizen of the United States, residing at Pittsburgh, county of Allegheny, and State 5 of Pennsylvania, have invented certain new and useful Improvements in Line-Holders, of which the following is a specification.

This invention relates to line holders and has for its object to provide a device of 10 such class, in a manner as hereinafter set forth, for tightly clamping the end of a rope or cable to prevent the slipping thereof until released.

Further objects of the invention are to 15 provide a line holder which is simple in its construction and arrangement, strong, durable, efficient and convenient in its use, readily set up, and comparatively inexpensive to manufacture.

20 With the foregoing and other objects in view the invention consists of the novel construction, combination and arrangement of parts, as hereinafter more specifically described and illustrated in the accompanying 25 drawings, wherein is shown an embodiment of the invention, but it is to be understood that changes, variations and modifications can be resorted to which come within the scope of the claim hereunto appended.

30 In the drawings wherein like reference characters denote corresponding parts throughout the several views:—

Figure 1 is a perspective view of a line holder in accordance with this invention 35 and further showing the adaptation thereof in connection with the clothes line, the holder being secured to a support.

Fig. 2 is a sectional side elevation.

40 Referring to the drawings in detail 1 denotes a plate provided with a depending extension 2 formed with an opening 3. Projecting upwardly from the plate 1 is a pair 45 of arms 4, 5, each having its outer face formed with an outwardly extending enlargement 6 provided with a pocket 7. Each of the arms 4, 5, has an opening 8 near its free end.

The reference character 9 denotes a clamping lever having each side, interme-

diate its end, formed with a laterally projecting lug 10 which is seated in a pocket 50 7 whereby the lever 9 is pivotally connected with the plate 1. When the lever 9 is coupled with the plate 1 it is disposed centrally with respect thereto. 55

Formed integral with the upper end of the lever 9 is a yoke 11, which is positioned above the top of the arms 4, 5, and carried by the lower end of the lever 9 is a transversely extending base 12, provided with a 60 pair of inwardly extending lugs 13, which are adapted to engage in openings 14, formed in the plate 1, when the lever 9 is in clamping position and the lugs 13 are employed to prevent the line 20 from slipping under the head 12. The lugs 13 are formed integral with the inner face of the base 12, and are positioned inwardly with respect to the ends of the base. 65

The openings 3, 8 are employed for the 70 passage of securing devices 15 to secure the plate 1 to the support 16.

What I claim is:—

A line clamp comprising a holder provided intermediate its ends with a pair of 75 outwardly extending enlargements each formed with a pocket, said enlargements spaced from each other, a clamping lever provided at each side and intermediate its ends with a laterally projecting lug seated 80 in one of the pockets whereby the lever is pivotally connected with the holder, said holder having formed therein between its lower end and said enlargements a pair of transverse alining openings spaced from 85 the sides of the holder, and said clamping lever including a transversely extending base having formed integral with its inner face near each end an inwardly extending lug, said lugs seating in said openings to 90 prevent slipping of a line from under the base.

In testimony whereof I affix my signature in the presence of two witnesses.

MATHIAS SMOLIK.
